CRANKING JACK FOR DIESEL ENGINES

Joseph H. Kobbe, Savanna, Ill.

Application June 16, 1945, Serial No. 599,935

7 Claims. (CL 254—131)

1

In timing valves of engines, "dead center marks" on the flywheel must be accurately established, and in checking the timing, as well as other familiar service operations, the "dead center marks" must be brought to and accurately stopped in position. With large Diesel engines, such as are used in locomotives, much power is required to turn the flywheel and crank shaft and associated parts, and its application must be under certain and definite control in order to stop the flywheel with the "dead center marks" exactly where they should be.

The principal object of this invention is to provide a simple instrument with which a man can easily turn and accurately control the flywheel of a large engine. Generally speaking, this is accomplished by means of a lever and ratchet device that can be operated between a fixed anchorage on the floor or foundation adjacent to the engine and selected points on the flywheel with great mechanical advantage.

A preferred embodiment of the invention is shown in the accompanying drawings, in which Fig. 1 is a perspective view of the cranking jack in operation;

Fig. 2 is a side elevation similar to Fig. 1 indicating positions of the lever in turning the flywheel; and

Figs. 3 and 4 are sections taken on the lines 3—3 and 4—4 of Fig. 1.

In these drawings, 10 indicates the floor or foundation of the engine represented by a fragment of the flywheel marked 11.

The cranking jack is made up of a mounting block A, a jack support B, a forked lever C, and a ratchet D.

The mounting block in a form that has been found practical is 2" wide, 2" high, and 1 $\frac{1}{2}$ " thick. It is pierced through the inner section of its diagonals, or in the center, by a $\frac{7}{8}$ " bore 12, and fitted at opposite sides with $\frac{1}{2}$ " trunnions 13, $\frac{5}{8}$ " long.

The jack support is composed of two angular pieces 14 made of $\frac{1}{2}$ " x $1\frac{1}{2}$ " bar stock, bent substantially at right angles at 15, and provided with $\frac{3}{2}$ " openings 16 and 17 adjacent to its opposite ends. The openings 16 receive the trunnions 13, by means of which rotary mounting is formed for the jack support. As here shown, the trunnions 13 have countersunk riveted ends 18.

The forked lever C includes two arms 20 formed from $\frac{1}{2}$ " x $1\frac{1}{2}$ " stock, bent at 21 and drawn down and rounded at 22 to be received snugly within a 24" length of 1" pipe 23.

2

The fork between the arms 20 is spanned by a $\frac{1}{2}$ " pin 24 with countersunk riveted heads flush with the outer sides of the arms 20, $2\frac{1}{4}$ " on centers from this pin. Each arm is provided with a $\frac{1}{2}$ " fulcrum pin 25 adapted to be received within the corresponding opening 17 by means of which the lever is fulcrumed to the end of the jack support adjacent to the flywheel.

The flywheel is provided with a series of openings 26, $1\frac{1}{8}$ " in diameter, arranged along the medial line of the periphery. Each of these is adapted to receive a $1\frac{3}{2}$ " shank 27, $2\frac{1}{4}$ " long on the stem 28 of the ratchet D, which includes a somewhat circular arm 29 provided with a series of teeth 30. The stem 28 is sufficiently large in proportion to the other parts mentioned when made of 2" stock, and the notches between the teeth 30 afford ample clearance when $\frac{5}{8}$ " is the radius at the bottom.

20 The jacking lever is made fast to the floor or foundation 10 by cap screw or stud 32 passed through the bore 12 and into the floor or foundation, as indicated in Figs. 1 and 4.

25 The assembly is deemed obvious from the description in connection with the various positions shown in the drawing. By comparison of Figs. 1 and 2, it will be seen that a man operating the forked lever C between the positions shown in Fig. 2 can readily rotate the flywheel in the direction 30 of the arrow in suitable increments of movement to bring the "dead center marks" to the exact position required. The arrangement described and the leverage afforded by parts of the dimensions given permit this to be accomplished by 35 very little effort. The rotation is all performed by a downward movement of the lever, and thus the weight of the operator does most of the work and very little actual manual strength is required to perform the rotation of the flywheel and associated parts.

40 It is obvious that the ratchet D may be inverted and operated to progressively turn the flywheel in the opposite direction, if desired, by merely lifting on the handle instead of forcing it downwardly.

45 Others will readily make variations in the construction and arrangement to suit particular conditions and to conform with personal preferences, but the foregoing, in connection with the drawings, is submitted as sufficient to disclose the principle of operation and the preferred embodiment.

I claim:

1. In a device of the class described, a jack support comprising angular side pieces journaled on

a mounting block adapted to be secured to a fixed foundation, a lever fulcrumed to the angular side pieces, and an arm having one end secured to a flywheel to be turned and having at its other end portion a series of spaced teeth for successive engagement with the lever.

2. In a device of the class described, a jack support adapted to be made fast to a fixed foundation, a lever fulcrumed at one end on the support and having a handle at its other end, and means connecting the lever with a flywheel to be turned, said means consisting of an arm having one end secured to the flywheel and having at its other end portion a series of spaced teeth for successive engagement with a point on the lever between the fulcrum and the handle.

3. In a device of the class described, a jack support pivoted to a fixed foundation, a lever fulcrumed on the support, and an arm having one end secured to a flywheel to be turned and having at its other end portion a series of spaced teeth for successive engagement with the lever, whereby swinging the lever about its fulcrum causes the support to rock about its pivot and brings the lever successively into engagement with teeth on the arm to turn the flywheel.

4. In a device of the class described, a jack support pivoted to a fixed foundation, a lever fulcrumed at one end on the support and having a handle at its other end, and an arm having one end secured to a flywheel to be turned and having at its other end portion a series of spaced teeth for successive engagement with a point on the lever between the fulcrum and the handle, whereby swinging the handle downwardly about the fulcrum causes the support to rock about its pivot and brings the lever successively into engagement with teeth on the arm to pull the arm downwardly and turn the flywheel.

5. In a device of the class described, an arm secured to a flywheel to be turned and having a series of teeth spaced along its length, and means for pulling the arm down comprising a support pivoted to a fixed foundation and a lever

fulcrumed on the support and having an element engageable with successive teeth as the lever is swung down toward the support, said support rocking on its pivot on each rise of the lever to enable the element to clear a tooth.

6. In a device of the class described, an arm secured to a flywheel to be turned and having a series of teeth spaced along its length, and means for pulling the arm down comprising a support pivoted to a fixed foundation and a lever fulcrumed at one end on the support and having at its other end an operating handle, and an element on the lever between the fulcrum and handle engageable with successive teeth as the handle is swung down toward the support, said support rocking on its pivot on each rise of the handle to enable the element to clear a tooth.

7. In a device of the class described, a support adapted to be anchored against movement in at least one direction, a lever fulcrumed on the support having a transversely extending tooth-engaging element and a handle on the lever for moving said element with mechanical advantage, and an arm adapted to be detachably anchored at selective points along the periphery of a flywheel to be turned and having a portion thereof extending adjacent to the periphery of the flywheel with a series of teeth therein adapted to be engaged by the tooth-engaging element of the lever to rotate the flywheel with mechanical advantage.
